UNITED STATES PATENT OFFICE.

FREDERICK STITZEL AND CHARLES WEINEDEL, OF LOUISVILLE, KENTUCKY,
ASSIGNORS TO THE AMERICAN SEMAPHORE COMPANY, OF SAME PLACE.

SEMAPHORE-SIGNAL.

SPECIFICATION forming part of Letters Patent No. 398,353, dated February 19, 1889.

Application filed March 24, 1888. Serial No. 268,406. (No model.)

To all whom it may concern:

Be it known that we, FREDERICK STITZEL and CHARLES WEINEDEL, of Louisville, in the county of Jefferson and State of Kentucky, have invented certain new and useful Improvements in Semaphore-Signals; and we do hereby declare the following to be a full, clear, and exact description of the invention, such as will enable others skilled in the art to 10 which it appertains to make and use the same.

Our invention relates to semaphore-signaling apparatus, and more particularly to such as employ the combined forces of electricity and pneumatics in their operation.

15 The object of our present invention is to provide a signaling device which shall be simple in construction and effective in operation.

A further object is to furnish a device to move a semaphore or other signal automatically when a train enters or leaves a block of 20 a railroad.

A further object is to provide a signaling apparatus in which fluid-pressure is employed as a motive power and electricity as a 25 controller.

A further object is to so construct the device that it shall have a small number of working parts, dispense with the use of stuffing-boxes and spring, and provide simple and efficient means by which fluid is admitted to 30 and emitted from the cylinder automatically.

With these objects in view our invention consists in certain novel features of construction and peculiar combinations and arrangements of parts, as will be hereinafter set forth, and pointed out in the claims.

In the accompanying drawings, Figure 1 is a sectional view of a signal-tower, showing the positions of the parts when the signal-blade is set at "danger." Fig. 2 is a similar view, partly broken away, and showing the positions of the parts when the signal-blade is at "safety." Fig. 3 is a side view showing the attachment of the apparatus to the visual signal-blades. Fig. 4 is a top plan view of the lever H.

This device is designed more particularly for use with railroads upon which the "block" system is employed, and will be described in 50 connection with such system. It is evident, however, that the signaling apparatus is

equally well applicable to other methods of railroad or other signaling.

A indicates a tower or structure, preferably of cylindrical form, and provided with suitable doors by which access may be had to the working parts. A steeple, A', will 55 advisably be projected above the roof of the main structure to furnish housing for mechanism which connects the visual blade with its actuating mechanism. At a suitable point in the height of the structure, preferably somewhat above its center, a floor or partition, A², is provided, which serves the twofold purpose of supporting the operative parts 60 composing the apparatus, and also producing a chamber, B, for the reception of compressed air for a purpose presently explained.

A pump, C, of any preferred construction, is placed upon the floor A² at or near the wall 70 of the structure, and provided with a handle, C', attached to the piston C², and projected through an opening, C³, made in the wall of the tower. A pipe, a, connects the pump C with the chamber or reservoir B 75 through the floor A², as shown in Fig. 1, the purpose of this pump being to force air into the chamber B, and the pump may, if desired, be located outside of the tower and put into communication with the air-chamber 80 in any suitable manner instead of being located within the tower, as above explained.

A cylinder, D, is secured to the under side of the roof of the structure by means of two or more laterally-projecting arms, b b, having 85 suitable fastening devices passing through them and into the roof. This cylinder D is preferably made in two parts or sections, D' D², the lower portion or cylinder proper, D², projecting downwardly from the supporting arms b at or about the center of the tower and the smaller portion, D', extending above the arms and into the steeple A', as shown in Figs. 1 and 2. Within the cylinder is located a piston-rod, E, adapted to have a reciprocating motion therein and provided at a suitable point in its length with a piston, E', to work within the cylinder proper, D², as presently explained, the upper end of this rod 90 extending into the upper portion, D', of the cylinder and the lower end projected some 95 distance below the cylinder, its downward

movement being limited by a stop, *f*, secured to the floor *A*².

Air is introduced to the upper end of the cylinder proper, *D*², by means of a pipe, *c*, which communicates with the air-chamber *B* through a double valve, *F*. This valve is advisably composed of a short tube, *d*, inserted through the floor *A*² at or near its center, and two disks or blocks, *d'* *d*², carried at opposite ends of a rod, *d*³, somewhat longer than the tube *d* and preferably supported by a spring, *d*⁴, secured at one end to the partition *A*² and bearing at its other end upon the end of the rod *d*³, said valve being controlled by means hereinabove described.

The cylinder *D*² is furnished with exhaust-ports *e* at points preferably below its center, as shown in Figs. 1 and 2.

Located upon the floor *A*², at a point preferably slightly distant from its center, is a standard or upright, *G*, for the support of a lever, *H*, pivoted to this standard in any suitable manner. The shorter arm, *H'*, of this lever is provided with an adjustable counter-balance-weight, *I*, while the extremity of the longer arm is furnished with a projection, *g*, adapted to engage a stop, *g'*, secured to the wall of the structure and prevent this end of the lever ascending too far. Directly above the fulcrum *h* of the lever *H* said lever is furnished with two integral ears, *i i*, which, being perforated, serve as bearings for journals of a short lever or stop, *J*, pivoted between them, the short arm of this lever being preferably bent slightly downwardly to engage a tapering projection, *J'*, formed upon or secured to the piston-rod *E*, which passes through a perforation, *J*², in the lever *H*, and prevent the upward movement of said rod when the parts are in the positions shown in Fig. 2. This lever or stop *J* will, however, yield and permit the stop on the rod *E* to pass it during the downward movement of said rod. The longer arm of the lever *H* is provided near its free end with ears *j j*, which serve as bearings for the journals of a lever or stop, *K*, adapted to yield when struck from one direction and remain rigid when engaged from the opposite direction.

A standard or upright, *M*, is mounted upon the floor *A*², near the wall of the structure, and carries at or near its upper end a pivoted T-lever, *N*, the depending arm *N'* of said lever being adapted to pass through a recess, *k*, made in one side of the lever *H*. A V-shaped projection, *N*⁴, on the arm *N'* of lever *N* engages the stop *K* of the lever *H*, and retains said lever in its horizontal position when the parts are in the position shown in Fig. 2. The outer end of the recess *k* of the lever *H* is preferably made beveled, and serves as a rest or abutment for the lower end of the arm *N'* of lever *N* when the parts assume the positions shown in Fig. 1. An arm, *N*², of lever *N* is furnished with a soft-iron armature, *O*, to be attracted by an electro-magnet, *O'*, supported directly over the armature by a bracket,

*O*², secured to the wall of the structure. Another arm, *N*³, of the lever *N* is adapted to make contact with the stop *g'*, and thus prevent the armature *O* from approaching too close to the magnet *O'*.

Mounted upon the arm *N*², between the fulcrum of the lever *N* and the armature *O*, is a block or washer, of leather, rubber, or other suitable material, *N*⁵, which, when the armature *O* is attracted by the magnet, will close the end of a pipe, *l*, which communicates with the cylinder *D*, preferably at or near the upper end of the portion *D*².

The valve *F* is operated by means of a depending arm, *P*, pivoted to the short arm *H'* of the lever *H*, near the fulcrum of the lever, and is provided at its lower extremity with an A-shaped head, *P'*, adapted to strike and move the valve when the lever *H* turns on its fulcrum to assume the position shown in Fig. 2.

The free ends of the wires leading from the electro-magnet *O'* are connected to the rails of a railroad-track (one wire to each track) at one end of a block, and a battery is electrically connected to the rails at the opposite end of the block.

Pivoted to the rod *E*, near its lower end, preferably just above the A-shaped head *m* at the lower end of said rod, is a yoke or frame, *Q*, advisably of metal. This yoke or frame, being thus pivoted to the rod *E*, is extended upwardly on the outside of the cylinder *D* and into the steeple *A'*, where its free ends are united by a rod or pin, *n*. The upright portions of the yoke *Q* are preferably passed through perforated lugs or ears projecting from the cylinder *D*, thus serving to guide the yoke *Q* in its movements.

Mounted in the steeple *A'* is a sprocket-wheel, *R*, carrying a visual-signal blade, *o'*; at one end of its shaft, said blade being preferably painted a different color from the shield, and adapted to be hid by the shield when the signal is set to indicate "safety." A drive or sprocket chain, *R'*, is passed over the wheel *R*, and has a weight, *R*², attached to one end, while the opposite end of said chain is secured to the rod *n* of the yoke *Q*. Thus it will be seen that as the yoke *Q* moves up and down, as presently explained, the signal-blade *o'* will be turned from its shield to exhibit a danger-signal or into its shield to indicate "safety."

The device being constructed as above described operates as follows: The tank or chamber *B* being filled with air or other fluid by means of the pump *C* or otherwise, and assuming the signal to be at "safety" and the parts in the position shown in Fig. 2, a train entering the block will short-circuit the battery and demagnetize the magnet *O'*. The electro-magnet *O'* being thus demagnetized, the lever *N* carrying the armature *O* will turn on its pivot and thus release the long arm of the lever *H* and open the valve *N*⁵. The weight *R*² of the chain *R'* overbalances the weight of

the rod E and attached parts, and consequently the stop J' on said rod bears upon the stop J of the lever H with a pressure exceeding that of the counterbalance-weight I on said lever. This being the case, as soon as the lever N is permitted to turn on its fulcrum the lever H is turned on its fulcrum by pressure of the stop J' against the stop J, and the end of the arm N' of the lever N will rest 5 on the inclined portion of the recess k and hold the lever H in an inclined position, as shown in Fig. 1. When the lever H releases the rod E, as above explained, said rod is caused to rise by the overbalance of the weight 10 R², the chain connecting this weight with the yoke Q causing the shaft carrying the visual signal to turn and thus exhibit said signal to view. The ends of the pipes c and l being open, the piston E' will be permitted to rise 15 freely, any air in the cylinder being allowed to escape through these pipes. When the lever H is turned, the rod P is caused to swing rearwardly slightly until the head P' is directly over the valve F. As soon as the train 20 leaves the block the electro-magnet O' is energized and attracts the armature O, causing the lever N to turn and close the end of the pipe l by contact of the washer N⁵ therewith. When the lever N is thus caused to turn, the 25 lever H will be released and caused, by the weight I, to assume a horizontal position and be retained in such position by engagement of the stop K with the projection N¹ of the lever N. As the lever H turns on its pivot, 30 the head P' of the rod P comes into contact with the valve F and closes the top of the tube d and opens the lower end thereof, thus 35 opening communication between the air-chamber B and the cylinder D through the pipe c. Compressed air being thus permitted to flow 40 into the cylinder above the piston E', said piston is caused to descend against the weight of the counter-balance R². This operation will cause the visual signal to be turned within 45 its shield through the medium of the chain operating upon the sprocket-wheel on the shaft of the signal-blade, thus signifying "safety." The rod E continues to descend until it reaches the stop f and the visual signal 50 is within the shield. During the descent of the rod E its enlarged end comes into contact with the head P' of the rod P and forces it off the valve F, allowing the valve to rise and shut off the air-supply from the cylinder. 55 The contained air in the cylinder will exhaust itself through the outlet e. When the piston-rod E is at its lowest position, the stop J' of the piston-rod will have passed the pivoted lever or stop J, and will be held thereby 60 against upward movement until the magnets are again demagnetized by the short-circuiting of their battery by a train entering the block, and the parts operate as above described. 65 Should the valve F fail to open to permit the air from the cylinder D to escape through the pipe c, or the piston-rod E fail to push

the head of the rod P off said valve, or the piston E' fail to uncover the exhausts e, the air in the cylinder will be permitted to exhaust through the pipe l, the end of said pipe being opened by the removal therefrom of the washer N⁵, in the manner hereinbefore explained. It will therefore be seen that by the employment of this pipe l and means for opening and closing the free end of the same the exhaust of air from the cylinder to permit the piston to rise when the signal is to be set at "danger" is rendered doubly certain.

Slight changes might be made in the constructive details of our invention without departing from the spirit thereof; hence we do not wish to limit ourselves to the exact details of construction herein set forth; but,

Having fully described our invention, what we claim as new, and desire to secure by Letters Patent, is—

1. In a signaling apparatus, the combination, with a cylinder and piston-rod, of a visual signal connected with the latter, a lever pivoted in close proximity to the piston-rod, this lever having a pivoted stop to engage the piston-rod, and mechanism to automatically release the piston-rod, substantially as set forth. 95

2. In a signaling apparatus, the combination, with a cylinder, a piston, and piston-rod, of a signal-blade connected with the latter, a fluid-pressure supply-pipe communicating with the cylinder, a lever pivoted in close proximity to the piston-rod, this lever having a pivoted stop to engage the piston-rod, and mechanism to automatically release the piston-rod, substantially as set forth. 100

3. In a signaling apparatus, the combination, with a cylinder made in two parts, one of said parts being larger in circumference than the other, of a piston in the larger portion, a piston-rod secured to said piston and adapted to reciprocate in both sections of the cylinder, a signal-blade connected with the piston-rod, a fluid-pressure inlet-pipe communicating with the cylinder, a lever pivoted in close proximity to the piston-rod, this lever having a pivoted stop to engage the piston-rod, and mechanism to automatically move the stop to release the piston-rod, substantially as set forth. 110 115

4. In a signaling apparatus, the combination, with a cylinder having inlet and outlet ports, of a piston and piston-rod, enlargements on the rod, a lever pivoted in close proximity to the piston-rod, this lever having a pivoted stop to engage one of said enlargements, a signal-blade connected with the piston-rod, and mechanism to automatically release the piston-rod to display the signal, substantially as set forth. 120 125

5. In a signaling apparatus, the combination, with a cylinder, and a piston and piston-rod, of a yoke or frame attached to the latter near its lower end and extending upwardly above the piston, a visual blade connected with the yoke, fluid-pressure inlet and outlet ports 130

- communicating with the cylinder, a pivoted stop to engage an enlargement on the piston-rod, and mechanism to automatically release said piston-rod and permit it and the yoke to rise and cause the signal-blade to be turned, substantially as set forth.
6. In a signaling apparatus, the combination, with a cylinder having perforated bosses on its exterior, and a piston and piston-rod, of a yoke or frame pivoted to the piston-rod near its lower end and passing through the perforated bosses on the cylinder, a visual-signal blade, a sprocket-wheel on the shaft of said blade, a chain carrying a weight at one end and connected at its opposite end to the yoke, and mechanism for actuating said piston to operate the signal-blade, substantially as set forth.
7. In a signaling apparatus, the combination, with a structure, a fluid-reservoir therein, and a pump for forcing fluid into said reservoir, of a cylinder, a pipe for connecting the reservoir with said cylinder, a valve in said pipe, a piston and piston-rod in the cylinder, a signal-blade connected with the piston-rod, and mechanism for operating the valve automatically just before the downward movement of the piston-rod to admit fluid to the cylinder, substantially as set forth.
8. In a signaling apparatus, the combination, with a fluid-reservoir, of a cylinder, a pipe connecting the reservoir and cylinder, a valve in said pipe, a piston and piston-rod in the cylinder, a visual signal connected with the piston-rod, a pivoted lever, a depending rod pivoted thereto, and mechanism for operating the lever to cause the depending rod to strike the valve and open the same, substantially as set forth.
9. In a signaling apparatus, the combination, with a fluid-reservoir, a cylinder, a piston and piston-rod, and a signal-blade connected with the latter, of a pipe connecting the reservoir and cylinder, a double valve communicating with the pipe, said valve being held open at one end by a spring, a pivoted lever carrying a depending rod, and mechanism to turn said lever and cause the depending rod to strike the valve to close one end and open the other, substantially as set forth.
10. In a signaling apparatus, the combination, with a cylinder, a piston and piston-rod therein, and a signal-blade connected with the latter, of a pivoted lever, a stop to engage an enlargement on the piston-rod, a T-lever to support one end of the first-mentioned lever and carrying an armature, and an electro-magnet to actuate said armature, substantially as set forth.
11. In a signaling apparatus, the combination, with a cylinder, a piston and piston-rod therein, and a signal-blade connected with the latter, of a lever carrying a counterbalance-weight, a stop pivoted to the lever to engage an enlargement on the piston-rod, a second pivoted stop near one end of the lever, a T-lever having an enlargement to engage this pivoted stop, an armature carried by the T-lever, and an electro-magnet to actuate the armature, substantially as set forth.
12. In a signaling apparatus, the combination, with a cylinder, a piston and piston-rod therein, and a signal-blade connected with the piston-rod, of a reservoir, a pipe connecting the cylinder and reservoir, a valve between the pipe and reservoir, a pivoted lever carrying a pivoted stop to engage an enlargement on the piston-rod, a pendulum-rod pivoted to the lever and adapted to strike the valve, an enlargement on the end of the piston-rod to strike the pendulum-rod to disengage the latter from the valve, a T-lever to support one end of the first-mentioned lever and carrying an armature, and an electro-magnet to attract said armature and retain the T-lever in place, substantially as set forth.
13. In a signaling apparatus, the combination, with a fluid-reservoir, a cylinder, a piston and piston-rod therein, and a signal-blade connected with the piston-rod, of a pipe connecting the reservoir and cylinder, a valve between the pipe and reservoir, a pivoted lever carrying an armature, an electro-magnet to attract said armature, a pipe connected with the cylinder and terminating above the lever, and a washer carried by said lever and adapted to close the end of the pipe, substantially as set forth.
14. In a semaphore-signaling apparatus, the combination, with the railroad-tracks, of a battery and an electro-magnet connected with said tracks at opposite ends of a block, a lever carrying an armature, a fluid-reservoir, a cylinder, a pipe connecting the reservoir and cylinder, a valve between the pipe and reservoir, a piston and piston-rod in the cylinder, a signal-blade connected with the piston-rod, and mechanism for operating the valve to admit fluid to the cylinder when the magnet is energized, substantially as set forth.
15. In a signaling apparatus, the combination, with a fluid-cylinder, a piston and piston-rod therein, and a visual signal connected with said rod, of a vibrating lever having an armature, an electro-magnet to attract the armature, a pipe connected with the cylinder and terminating near the armature, and mechanism carried by said lever and adapted to open and close the pipe, substantially as set forth.

In testimony whereof we have signed this specification in the presence of two subscribing witnesses.
